UNITED STATES PATENT OFFICE

GEORGE E. PRENTICE, OF BERLIN, CONNECTICUT

SEPARABLE FASTENER

Application filed March 1, 1930. Serial No. 432,388.

This invention pertains to separable fasteners of that type in which independent fastener units are secured to the edge of a flexible tape or stringer, and relates more particularly to an improved fastener unit and to a method of making the same. The patent to Judson, No. 788,317, dated April 25, 1905, discloses a separable fastener wherein each independent unit consists of a split sleeve 10 adapted to embrace the beaded edge of the tape or stringer, the units of one series having projecting tongues or hooks which enter suitable sockets in the units of the opposite series, each socket being defined partly by 15 the wall of the unit and partly by the edge of the enclosed stringer. In the Judson fastener the tongues or hooks thus directly engage the edge of the stringer of the opposite series, and this tends to cause wear and 20 roughening of the stringer. Moreover, the tongues and sockets are of such shape that the fastener is not as flexible as could be desired, and the units must be made of unduly heavy material and of undesirable thickness 25 from front to rear in order to insure a firm grip on the edge of the stringer. In the Judson construction the units are of two distinct types, one type having the socket and the other type having the tongue for engagement 30 therewith, which is a disadvantage from the manufacturing standpoint, and the units are of such shape that when cut from sheet material, a large percentage of waste results.

I am aware that various attempts have 35 been made to improve upon the Judson type of fastener, but do not know of any fastener employing sheet metal units in which all of the above noted defects have been successfully overcome. For example, as respects 40 certain methods of manufacture now in use, a wastage of as much as 75% of the sheet material results.

In accordance with the present invention I 45 provide a fastener unit which may consist of relatively thin sheet material, but which at the same time is capable of gripping the edge of the stringer securely and permanently; which, in a preferred embodiment, provides protection for the inner edge of the stringer 50 so that the tongue or retaining element of the

cooperating unit does not wear or abrade the stringer (being received within a socket having rigid walls); which provides a tongue and socket of such shape that the fastener is flexible when the opposed series of units are 55 joined; which may be used with sliders of usual construction; which is not unduly thick so as to cause a bulky seam; and which may be made from sheet material without appreciable waste.

In the accompanying drawings I have illustrated certain desirable embodiments of my invention by way of example, as well as certain steps which may usefully be employed in the production of this improved fastener 60 unit, and in the drawings:

Fig. 1 is a fragmentary front elevation to large scale illustrating a fastener comprising units embodying my invention and showing an actuating slider of conventional form, in 70 section;

Fig. 1^a is a perspective view showing a completed unit, but without the stringer;

Fig. 2 is a diagrammatic view illustrating the mode of cutting sheet material without 75 waste to produce blanks for use in making the improved fastener;

Fig. 3 is a plan view of such a blank to larger scale;

Fig. 4 is an edge view, to smaller scale, of 80 the blank of Fig. 3;

Figs. 5, 6, 7, 8 and 9 illustrate various steps in the process of bending the blank to form the complete unit;

Fig. 10 is a view showing a blank of substantially the same shape as that of Fig. 3;

Figs. 11, 12, 13 and 14 are views showing a desirable sequence of steps in forming the fastener unit of slightly modified construction, starting with the blank of Fig. 10; and

Fig. 15 is a fragmentary section to large scale illustrating one type of material which may, if desired, be employed in making fastener units.

Referring to the drawings, and particularly to Fig. 1, the numerals 1 and 2 designate pieces of flexible material such as the tapes or stringers commonly employed in devices of this character for attaching the fastener units to the edges of the article having the 100

gap to be closed. As here shown the stringers 1 and 2 are provided with thickened or beaded edges 3 to which are secured the fastener units 4. A slider 5, which may be of any usual type having convergent channels 6 for the reception and guidance of the opposed series of fastener elements, is mounted to slide longitudinally of the series for moving the units into and out of engagement in usual manner.

Referring to Fig. 1^a, a preferred embodiment of my invention consists of a unitary piece of sheet metal bent to form a more or less rectangular structure having the wall 7 and the substantially parallel, spaced side walls 8 and 9. For convenience in description I shall hereinafter refer to the wall 7 as the "front" wall, this being the surface of the fastener unit which is opposed to the units of the opposite series, although when in actual use one of the walls 8 or 9 would ordinarily be considered as the front wall. As here shown, the front wall 7 is substantially flat and perpendicular to the walls 8 and 9, although I contemplate that the wall 7 may, if desired, be curved either convexly or concavely, or otherwise suitably shaped for cooperation with the opposed units. The wall 7 is provided, as here shown, at its lower edge with an integral extension or projection 10 which constitutes a tongue, hook, or retaining element for engagement with a unit of the opposite series. In referring to this hook member 10 as projecting from the "lower" edge of the wall 7, I employ the term "lower" in a relative sense only, since under various conditions of use the hook may not always project vertically down.

The material forming the walls 8 and 9 is bent at the rear ends of said walls, as shown at 11 and 12, preferably to form open bends, the material then extending inwardly, as shown at 13 and 14, to form jaws for engaging the beaded edge of the stringer. As shown, these jaws 13 and 14 diverge in a forward direction and their forward extremities are bent to provide the shield members 15 and 16 which, with the jaw members 13 and 14, define a pocket or recess 17 in which the beaded edge of the stringer is disposed. By reason of the open bends at 11 and 12, the entrance 18 to this recess forms a restricted neck through which it is practically impossible to pull the thickened or beaded edge of the stringer. The members 15 and 16 also cooperate with the front wall 7 and the forward portions of the side walls 8 and 9 to form a socket 19 of substantially rectangular section for the reception of the hook member 10 of the cooperating unit of the opposite series. The members 15 and 16 thus separate the cooperating hook member from the edge of the stringer and shield the latter from abrasion and wear.

In constructing this improved unit I may

employ any suitable sheet material which may, for example, be metal, or metal combined with other materials, or in fact, any substance capable of retaining its shape permanently after bending. In Fig. 15 I have indicated a material which might well be used for the purpose, consisting of a base sheet M of strong, stiff material such as metal, and a coating or covering layer C, which may, for example, be a suitable enamel, a phenol-condensation product, a lacquer, a rubber compound, or, in fact, any suitable coating substance adapted to protect or ornament the base material, and which may be caused to adhere firmly and permanently to the base material in any proper way, as by the interposition of a uniting layer U. This sheet material, of whatever kind, may now be cut into blanks 21 (Fig. 2) of the shape more particularly shown in Fig. 3. Each blank, as shown, comprises an elongate trapezoidal body portion 22 having the long base 23 and the short base 24, and from the central part of its short base 24, a trapezoidal hook-forming member 25 projects, the longer base of the member 25 being integrally united with the body member 22. As shown, the longer base of the projection 25 is approximately one-seventh the length of the longer base 23 of the body portion, although this proportion is not essential, but it will be noted that the altitude of the projection 25 is substantially equal to the altitude or transverse width of the body portion 22, and that corresponding angles, as for example the angles A and A', of the projection and body portion are equal to each other. Blanks of this general shape may, as indicated in Fig. 2, be cut from sheet material with no waste whatever.

Having produced a blank as above described, this blank is now bent (as shown in Fig. 5) transversely along lines such as 26 and 27 (Fig. 3) to form the shield members 15 and 16. The blank is also bent, but in reverse direction, along the transverse lines 28 and 29 to produce the open bends 11 and 12, thereby defining the jaws 13 and 14 and the rear ends of the walls 8 and 9, the open bends at 11 and 12 greatly stiffening the unit. The blank also is bent transversely at opposite edges of the base of the projection 25 to define the junctions of the side walls 8 and 9 with the front wall 7. These several bending operations may be performed in any desired sequence, although the sequence indicated in Figs. 4 to 9 is preferred. When the blank has been brought to the shape shown in Fig. 8, the beaded edge of the stringer is introduced between the jaw members 13 and 14, and then as the walls 8 and 9 are brought into substantially parallel relation the beaded edge is securely jammed between the jaw members so that it is, to some extent, deformed and crushed, and is thus very securely retained by the jaws so that it can not be

pulled from between them. At the same time, as will be noted in Fig. 9, the shield members 15 and 16 substantially cover the inner edge of the bead and thus the socket 19 is provided with a substantially continuous rigid wall.

The fastener units of both series are of identical construction and are so staggered with relation to each other with the hook member 10 of the unit of one series engages within the socket 19 of a unit of the other series. By reason of the substantially rectangular shape of these units, they may be employed with sliders of a type commonly used at present, and by reason of the trapezoidal shape of the hook members, they are able to rock slightly in a lateral direction in their receiving sockets, so that the fastener as a whole is flexible and capable of bending without disengagement of the interlocking units. As already pointed out, these units may be made without waste from sheet material by a simple series of bending operations such as may be produced by proper dies, and thus the units may be formed very cheaply and with great rapidity and may be secured to the edge of the fabric by hand or by the use of automatic mechanism of simple type.

Referring to Figs. 10 to 14 inclusive, the blank 21^a is bent transversely to form the jaws 13^a and 14^a and the extremities of these jaws are then angularly bent to form the inner members 15^a and 16^a. In this construction, the front wall is preferably struck out, as shown at 30, to form a socket member for the reception of the opposed hook, and the side walls 8^a and 9^a are brought into parallelism, with the beaded edge of the stringer 2 interposed between them. This form of unit has certain advantages of that previously described, but does not provide the protection for the edge of the stringer which is afforded by the unit shown in Fig. 1^a, for example.

While the specific construction and the process steps above described in detail are desirable, I wish it to be understood that the invention is not necessarily limited to all of the particulars of such construction or process, but that various changes including omission of elements or process steps, as well as the substitution of equivalents, may be made without departing from the invention as set forth in the appended claims.

I claim:

1. A fastener unit consisting of a single elongate piece of sheet metal having substantially parallel upper and lower edges with a hook member projecting from the central part of one of said edges for engagement with a cooperating fastener unit the metal being so bent that the part from which the hook projects constitutes the front wall of a socket for the reception of the hook member of a cooperating fastener unit of like construction, and that those parts of the strip at opposite

sides of said central portion define side and rear walls of said socket and also define a separate pocket for the reception of the edge of a stringer, said pocket having a restricted neck to accommodate the material of the stringer.

2. A fastener unit for use with a stringer having a beaded edge, said unit consisting of sheet material and comprising a front wall and walls spaced to receive between them the beaded edge of the stringer and also the retaining element of a cooperating unit of similar construction, and means integral with the respective walls and disposed between the latter for embracing the beaded edge of the stringer without penetration of the latter and means comprising parts having free extremities collectively acting to shield the edge of the stringer from the retaining element.

3. A fastener unit consisting of a single elongate piece of sheet material having its upper and lower edges disposed in parallel planes and having projecting from one of said edges a hook member for engagement with a cooperating fastener unit of similar construction, and parts bent to define a socket for the reception of the hook member of such cooperating fastener unit and also defining a smooth walled recess for the reception of the edge of a stringer, certain of said parts having free extremities collectively constituting shielding means for the edge of the stringer to protect it from injury by the hook member of the cooperating unit.

4. A fastener unit of sheet material for use in separable fasteners, said unit comprising a front wall and substantially parallel spaced side walls integrally united therewith, and cooperating jaws, one secured to the rear edge of each of the side walls, said jaws extending inwardly between the side walls of the unit and defining a pocket for the edge of a fabric stringer, said jaws being free at their inner extremities.

5. A fastener unit of substantially rectangular contour consisting of a unitary piece of sheet material bent to form front and side walls, the front wall having an integral hook extending therefrom, the material constituting the side walls being bent at the rear ends of said walls to form smoothly rounded clamping jaws for engaging and retaining the edge portion of a stringer the material of the respective jaws being continued forwardly between the side walls and forming a shield for the stringer and constituting the rear wall of a hook receiving socket.

6. A fastener unit for use in separable fasteners, said unit comprising a single piece of sheet material shaped to provide a front wall, spaced side walls integrally united to the lateral edges respectively of the front wall, the side and front walls being of sub-

stantially the same height, and a hook integrally united to the lower edge of the front wall and disposed in the same plane with the latter the hook projecting from said edge to a distance substantially equal to the depth of the front wall.

7. A fastener unit for use with a stringer having a beaded edge, said unit consisting of sheet material and having spaced side walls and independent jaw members secured respectively to the rear ends of the two side walls and extending inwardly between the side walls, said jaws having free inner extremities, the jaws diverging forwardly to provide a recess relatively wide at its forward part for the reception of the bead of the stringer, and relatively narrow at its rear part to prevent withdrawal of the bead from the recess.
8. A fastener unit for use with a stringer having a beaded edge, said unit consisting of a piece of sheet material and comprising spaced side walls having integral continuations thereof bent to extend inwardly between the side walls to form stringer retaining jaws, said jaws having spaced inner extremities, said jaws being spaced further apart at their front ends than at their rear ends whereby to admit and retain the beaded edge of the stringer between them.

9. A fastener unit for use with a stringer having a bead at its edge, said unit consisting of a piece of sheet material and comprising spaced side walls, the material at the rear end of each side wall turning inwardly with an open bend to form a retaining jaw, said jaws being free at their inner ends, the two jaws diverging to provide a bead receiving recess having a narrow neck.

10. A fastener unit for use with a stringer having a bead at its edge, said unit consisting of an integral piece of sheet material and comprising a front wall and spaced substantially parallel side walls perpendicular to the front wall, the material at the rear edge of the side walls turning inwardly and then extending forwardly to form jaws defining a bead receiving recess having a narrow entrance neck, the front wall having an integral extension constituting a hook for engagement with a cooperating fastener unit.

11. A fastener unit for use in separable fasteners, said unit comprising front and side walls, jaw members extending inwardly and forwardly from the rear ends of the side walls, said jaw members being shaped to retain the edge of a stringer disposed between them, the inner ends of the jaws being free and being spaced from the front wall of the unit to provide a socket for the reception of the retaining element of a cooperating unit, and a hook attached to the front wall.

12. A fastener unit for use with a stringer having a bead at its edge, said unit consisting of an integral piece of sheet ma-

terial and comprising a front wall and side walls, the side walls being spaced apart to admit between them the beaded edge of the stringer, the rear portions of the side walls turning inwardly toward each other and having extensions directed forwardly in divergent relation to define a pocket having restricted entrance passage through which the bead can not be withdrawn.

13. A fastener unit for use with a stringer having a bead at its edge, said unit consisting of a piece of sheet material and comprising a front wall and spaced side walls, the material at the rear end of each side wall turning inwardly with an open bend to form a retaining jaw, the two jaws diverging toward the front of the unit, each jaw having a shield member at its forward end, said jaws with their shield members defining a recess for the reception of the beaded edge of the stringer, the shield members with the front and side walls of the unit defining a socket for the reception of the retaining element of a cooperating unit.

14. A fastener unit for use with a stringer having a bead at its edge, said unit consisting of sheet material and comprising front and side walls, the material at the rear ends of the side walls turning inwardly and then extending forwardly to form jaws defining a bead receiving recess, the forward extremities of said jaws being directed toward each other to form shields for the bead disposed in said recess, and being spaced from the front wall of the unit to define a socket for the reception of the retaining element of a cooperating unit.

15. A fastener unit for use in separable fasteners, said unit comprising a piece of sheet material having an elongate trapezoidal body portion having substantially straight and parallel upper and lower edges and a hook member of trapezoidal shape having its longer base integrally united to the central part of one of the longer edges of the body portion, said hook member being disposed substantially in the plane of the central part of the body portion, the body portion being bent transversely to form a socket for the reception of the hook member of a cooperating unit and to provide parts adapted to embrace and retain the edge portion of a flexible stringer and to protect said edge from contact with the hook of a cooperating unit.

16. A fastener of the class described comprising opposed series of fastener units, each series being mounted upon a flexible stringer having a bead at its edge, all of the units including those of both series being substantially alike, each unit consisting of a single elongate piece of sheet material having substantially parallel upper and lower edges and a hook member projecting from one of said edges and adapted to engage a unit of

the opposite series, said sheet material being so bent as to provide parts defining an enclosure for the reception of the beaded edge of the stringer and another enclosure for the reception of the hook member of a cooperating unit, said parts including jaws so constructed and arranged as snugly to embrace and retain the edge of the stringer without penetration of the latter, and to shield said edge from the hook member of the cooperating unit.

17. A fastener unit for use in separable fasteners, said unit comprising a piece of sheet material of elongate trapezoidal shape having a trapezoidal projection integrally united to the central part of the shorter base of the body portion, the altitude of the projection being substantially equal to the altitude of the body portion, said projection constituting a hook for engagement with a cooperating fastener unit, the body portion being bent transversely to form a socket for the reception of the hook of a cooperating unit and to provide parts which embrace and retain the edge of a fabric stringer.

18. A fastener unit for use in a separable fastener comprising a piece of sheet material having an elongate trapezoidal body portion with a trapezoidal projection integrally united at its longer base to the central part of the shorter base of the body portion, said projection constituting a hook for engagement with the cooperating fastener unit, the body portion being bent transversely at points spaced from its ends to provide opposite jaws adapted to receive the edge of a stringer between them, the ends of the body portion extending forwardly beyond the jaws and forming the rear wall of a socket which receives the hook of the cooperating unit.

Signed by me at Berlin, Conn., this twenty-seventh day of February, 1930.

GEORGE E. PRENTICE.
